J. W. KAUFMANN.
REPRODUCER FOR TALKING MACHINES.
APPLICATION FILED JUNE 21, 1920.

1,381,201.

Patented June 14, 1921.

UNITED STATES PATENT OFFICE.

JOHN W. KAUFMANN, OF BALTIMORE, MARYLAND.

REPRODUCER FOR TALKING-MACHINES.

1,381,201.

Specification of Letters Patent. Patented June 14, 1921.

Application filed June 21, 1920. Serial No. 390,482.

To all whom it may concern:

Be it known that I, JOHN W. KAUFMANN, a citizen of the United States, and a resident of Baltimore, in the State of Maryland, have invented certain new and useful Improvements in Reproducers for Talking-Machines, of which the following is a specification.

My invention is an improvement in reproducers for talking machines, and has for its object to provide a new and improved connection between the needle and the diaphragm controlling lever, for improving the tone, making the reproduction more faithful and distinct, and eliminating the disagreeable machine element of the tone.

In the drawings:

Figure 1 is a front view of the improved reproducer,

Fig. 2 is a section on the line 2—2 of Fig. 1,

Fig. 3 is a partial plan view of the spring,

Fig. 4 is a front view of the needle holder and support,

Fig. 5 is a plan view of a modified form of needle holder,

Fig. 6 is an edge view of a modified form of spring before bending,

Fig. 7 is a partial front view, showing a modified mounting for the reproducer lever,

Fig. 8 is a section on the line 8—8 of Fig. 7.

In the embodiment of the invention shown in Figs. 1 to 3, the case one of the reproducer box has the usual central nipple 2

35 for receiving the inlet end of the amplifier 3, and the diaphragm 4 is held in the case between gaskets 5, by means of curved plates 6 and 7, the plate 7 being at that side of the case adjacent to the needle holder, while

40 the plate 6 is at the opposite side.

The reproducer lever 8 is connected to the diaphragm at the center thereof in the usual manner, by means of an angular portion of the lever, and the outer end of the lever is

45 connected to one end of a plate spring 9.

The needle holder 10, which has the usual means, indicated at 11, for holding the needle 12 in place, is provided at the end remote from the needle with a cross 13—14.

50 The arms 13 of the cross extend transversely of the end of the spring 9, while the arms 14 extend longitudinally of the said spring.

These arms are secured to the said spring by means of screws 15, and referring to Fig. 2

55 it will be seen that each arm of the cross has at its free end an enlargement which abuts

the spring, thus spacing the central portion of the arms away from the spring; that is, the arms of the cross only touch the spring at their extremities. Referring to Fig. 4, 60 it will be seen that the arms 13 of the cross are enlarged laterally at the openings for the screws. This permits a smaller amount of metal to be used, while at the same time securing a firm attachment. 65

The reproducer lever 8 is connected to the spring 9 at the end remote from the needle holder, by means of a plate or cross-head 16 integral with the said lever. This plate is secured to the spring by means of 70 screw 17, and referring to Fig. 2 it will be seen that the plate has extensions, or enlargements, at the screws for spacing the spring from the plate, in the same manner as the spring is spaced from the cross. 75

The ends of the arms 13 of the cross have depressions which receive tapering pointed pivot screws 18. These screws are threaded through bearing brackets 19 on the plate 7 before mentioned, and each screw is engaged 80 by a lock nut 20 outside the bearing. The plate 7 is of greater thickness than the plate 6, as clearly shown in Fig. 2, and the plate 16 of the reproducing lever has outwardly extending journal pins 21, which are pointed 85 as shown, and are engaged by set screws 22, which are threaded through outwardly extending bearings 23 on a radial extension 24 extending outwardly from the sound box in the opposite direction from the needle 90 holder.

The lock nuts 25 engage the screws outside of the bearing to hold them in adjusted position; thus the reproducing lever is pivotally supported at its outer end and 95 may rock freely on the said pivotal connection.

Referring to Figs. 1 and 3, it will be seen that the spring 9 is of greatest width at the end adjacent to the needle holder and of 100 least width at the end adjacent to the reproducer lever. The sides of the spring converge toward the reproducer lever, so that the spring as a whole tapers from the needle holder to the reproducer lever. Thus the 105 strength of the spring gradually decreases from the needle holder to the reproducer lever.

When the needle vibrates from its contact with the hills and hollows of the groove of 110 the record, that end of the spring to which the needle holder is connected is vibrated.

Because of the cross arms 14, the needle exerts considerable leverage upon the spring, and this movement is amplified and at the same time softened during its passage from 5 the large end to the small end of the spring. Thus a large part of the disagreeable machine element in the tone is eliminated, and because of the amplification of the movement of the needle holder, the sounds are 10 very distinct, while at the same time they are of a soft, agreeable quality.

The tapering of the spring is for the purpose of gradually decreasing the rigidity of the connection between the needle holder 15 and the reproducer lever from the needle holder to the reproducer lever, and this end may be attained otherwise than by lessening the width of the spring as, for instance, with the spring plate shown in Fig. 6 and indicated at 25, the amplification movement is brought about by gradually reducing the thickness of the spring from that end which is to be connected to the needle holder toward the opposite end. In either construction, 25 that end of the spring which is connected to the reproducer lever tapers outwardly, or broadens slightly, as clearly shown at 26 in Fig. 3.

In Fig. 5 there is shown modified construction of needle holder. The needle holder 27 has cross arms 28 and 29 corresponding to the arms 13 and 14 of Fig. 4. These arms have enlargements, or extensions, on the face adjacent to the spring, as 35 indicated at 30 and 31 respectively, and it will be noticed that the enlargements 31 are of greater depth than the enlargements 30; thus when the screws which connect the spring 2 to the cross arms are turned tightly 40 home, the spring will be slightly bowed laterally, which tends to improve the tone.

In each arrangement, the object is to provide relative rigidity at the needle holder end, with relative flexibility at the diaphragm end, so that the movement of the needle is imparted without lessening to the adjacent end of the spring, and because of the lessening resistance of the spring, the movement of the needle is amplified and 45 softened as it progresses toward the reproducer.

In the modified construction shown in Figs. 7 and 8, the reproducing lever 32 has an attaching plate 33 at its outer end, which 55 is connected to the spring 34 by means of screws 35. The plate 33 is mounted to rock on wedge-shaped pivot pins 36, which extend outwardly from the sound box 37. These pins engage indentations in the adjacent edge of the plate 33. Screws 38 are 60 passed through the extended ends of the plate 33 into engagement with the sound box 37, the said sound box having a radial extension 39 to which the screws are connected, and a sleeve 40 is arranged between

each screw head and the plate 33. As clearly shown in Figs. 7 and 8, the sleeves 40 are wedge-shaped, and the pointed ends of the sleeve engage indentations in the extended ends of the plate 33.

It will be understood that the improved reproducer is adapted for use as well with the type of record in which the indentations, that is, the hills and hollows, are lateral, as well as those which are in the bottom of the 70 groove.

I claim:—

1. In reproducers, the combination with the sound box and the diaphragm, and the reproducer lever connected with the diaphragm, of a needle holder pivoted to the sound box at one side of the diaphragm, a pivotal connection between the outer end of the reproducer lever and the sound box, and a spring connecting the reproducer lever at 80 the pivotal mounting with the needle holder, said needle holder having a relatively broad base for connection with the spring, said base being in the form of a cross, having arms extending longitudinally and laterally 85 of the spring in both directions from the needle holder.

2. In reproducers, the combination with the sound box and the diaphragm, and the reproducer lever connected with the diaphragm, of a needle holder pivoted to the sound box at one side of the diaphragm, a pivotal connection between the outer end of the reproducer lever and the sound box, and a spring directly connected at one end 95 to the reproducer lever at the pivotal mounting and similarly connected at its opposite end to the needle holder, said connection gradually decreasing in strength and resistance from the needle holder toward the 100 reproducing lever.

3. In reproducers, the combination with the sound box, and the reproducer lever and the needle holder pivoted at opposite sides thereof, of a spring directly connected at its 110 opposite ends to said lever and said needle holder and gradually decreasing in strength and resistance from the needle holder toward the reproducing lever.

4. In reproducers, the combination with the sound box, and the reproducer lever and the needle holder pivoted at opposite sides thereof, of a plate spring connecting said lever and needle holder, said needle holder having a cross-shaped base for connection with the spring, and the arms of the cross having enlargements at their ends for spacing the central portion of the cross from the spring, the enlargements at the ends of those arms which extend longitudinally of 120 the spring being of greater height than the other enlargements.

5. In reproducers, the combination with the sound box, and the reproducer lever and the needle holder pivoted at opposite sides 130

thereof, of a plate spring connecting said lever and needle holder, said needle holder having a cross-shaped base for connection with the spring, and the arms of the cross having enlargements at their ends for spacing the central portion of the cross from the spring.

6. In reproducers, the combination with

the sound box, and the reproducer lever and the needle holder pivoted at opposite sides thereof, of a plate spring connecting said lever and needle holder, said needle holder having a cross-shaped base for connection with the spring.

JOHN W. KAUFMANN.
